UNITED STATES PATENT OFFICE.

ALVA D. GARDNER, OF NORWALK, OHIO.

DESIGN FOR A LENS FOR GLASSES AND SPECTACLES.

54,405.

Specification for Design.

Patented Feb. 10, 1920.

Application filed February 21, 1916. Serial No. 79,790. Term of patent 14 years.

To all whom it may concern:

Be it known that I, ALVA D. GARDNER, a citizen of the United States, residing at Norwalk, in the county of Huron and State of Ohio, have invented a new, useful, and ornamental Design for Lenses for Glasses and Spectacles, of which the following is a specification, reference being had to the accompanying drawing, forming part thereof.

The edges of the lenses are beveled and polished.

Figure 1 is a plan view of the lens showing my design.

Fig. 2 is a cross section thereof on the dotted line II—II of Fig. 1.

I claim:

The ornamental design for a lens for glasses and spectacles, as shown.

ALVA D. GARDNER.
